FOLDING CAMPER

Bjarne Sollie, Jar, Norway, assignor to Wideroe Industri
A/S, Oslo, Norway, a Norwegian corporation

Filed July 2, 1968, Ser. No. 12,597

Term of patent 14 years

Int. Cl. D12—10

U.S. Cl. D14—3

Fig. 1.

Fig. 2.

Fig. 3.

Fig. 4.

Fig. 5.

Fig. 6.

FIG. 1 is a rear perspective view of the camper in erected form, partly broken away, to show the inside thereof with one of the upper bunks mounted;

FIG. 2 is a rear perspective view of the camper in folded position;

FIG. 3 is a left side perspective view of the camper in erected form with the rear door open;

FIG. 4 is a right side perspective view of the camper in erected form;

FIG. 5 is a front perspective view of the camper in folded position; and

FIG. 6 is a front perspective view of the camper in erected form, partly broken away, to show the inside thereof with the rear door open.

I claim:

The ornamental design for a folding camper, as shown and described.
